UNITED STATES PATENT OFFICE

148,501

DESIGN FOR A CAN OPENER

Albert M. Travis, Kansas City, Kans., assignor to
John C. Hockery, Kansas City, Mo., as trustee

Application July 29, 1946, Serial No. 132,085

Term of patent 14 years

(Cl. D22—2)

To all whom it may concern:

Be it known that I, Albert M. Travis, a citizen of the United States, residing at Kansas City, in the county of Wyandotte and State of Kansas, have invented a new, original, and ornamental Design for a Can Opener, of which the following is a specification, reference being had to the accompanying drawing, forming part thereof, in which

Fig. 1 of the drawing is a perspective view showing the front, top and one side of a can opener embodying my new design,

Fig. 2 of the drawing is a perspective view showing the front, top and opposite side of the can opener illustrated in Fig. 1, and

Fig. 3 is an elevational view showing the top of the can opener illustrated in Figs. 1 and 2.

I claim:

The ornamental design for a can opener, substantially as shown.

ALBERT M. TRAVIS.
